CLAIM

The ornamental design for a storage box, as shown and described.

DESCRIPTION

FIG. 1 is a top perspective view of a storage box showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top perspective view of an alternative embodiment of a storage box showing my new design;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a top perspective view of another alternative embodiment of a storage box showing my new design;

FIG. 16 is a front view thereof;

FIG. 17 is a rear view thereof;

FIG. 18 is a left side view thereof;

FIG. 19 is a right side view thereof;

FIG. 20 is a top plan view thereof;

FIG. 21 is a bottom plan view thereof;

FIG. 22 is a top perspective view of still another alternative embodiment of a storage box showing my new design;

FIG. 23 is a front view thereof;

FIG. 24 is a rear view thereof;

FIG. 25 is a left side view thereof;

FIG. 26 is a right side view thereof;

(Continued)

FIG. 27 is a top plan view thereof;
 FIG. 28 is a bottom plan view thereof;
 FIG. 29 is a top perspective view of yet another alternative embodiment of a storage box showing my new design;
 FIG. 30 is a front view thereof;
 FIG. 31 is a rear view thereof;
 FIG. 31 is a left side view thereof;
 FIG. 33 is a right side view thereof;
 FIG. 34 is a top plan view thereof;
 FIG. 35 is a bottom plan view thereof;
 FIG. 36 is a top perspective view of yet still another alternative embodiment of a storage box showing my new design;
 FIG. 37 is a front view thereof;
 FIG. 38 is a rear view thereof;
 FIG. 39 is a left side view thereof;
 FIG. 40 is a right side view thereof;
 FIG. 41 is a top plan view thereof; and,
 FIG. 42 is a bottom plan view thereof.
 The broken lines are included for illustrating portions of the storage box and form no part of the claimed design.
